SWITCHING APPARATUS

Charles C. Whittaker, Pittsburgh, Pa., assignor to
Westinghouse Electric Corporation, East Pittsburgh,
Pa., a corporation of Pennsylvania

Application June 29, 1944, Serial No. 542,735

5 Claims. (Cl. 201—51)

1

My invention relates, generally, to switching apparatus and, more particularly, to switches of the carbon-break type.

An object of my invention, generally stated, is to provide a carbon-break switch which shall be simple and efficient in operation and which may be economically manufactured and installed.

A more specific object of my invention is to provide a carbon-break switch which opens an electric circuit in a multiple number of places simultaneously.

Another object of my invention is to provide for inserting a high resistance into an electric circuit before it is opened by a carbon-break switch.

A further object of my invention is to provide a carbon-break switch in which the carbon pile is shunted from the circuit while the switch is carrying current continuously.

Other objects of my invention will be explained fully hereinafter or will be apparent to those skilled in the art.

In accordance with one embodiment of my invention, certain of the carbon discs of a carbon-break switch are deflected to make contact at their edges when pressure is applied along the longitudinal axis. As the pressure increases, the resistance through the discs decreases, and finally the carbon pile is shunted from the circuit. When the pressure is decreased, the first movement reinserts the carbon pile into the circuit while still compressed. As the pile expands, the resistance increases greatly and then the discs separate simultaneously at a plurality of different places, thereby providing a multiple-break switch.

For a fuller understanding of the nature and objects of my invention, reference may be had to the following detailed description, taken in conjunction with the accompanying drawing, in which:

Figure 1 is a view, partially in elevation and partially in section, of a switch embodying my invention;

Fig. 2 is a view, in plan, of the switch shown in Fig. 1, portions being broken away for clarity, and

Fig. 3 is an enlarged view, in section, of a portion of the carbon pile utilized in the switch.

Referring to the drawing, the structure shown therein comprises a base 10 on which is mounted a carbon pile assembly 11, an air cylinder 12, and a magnet valve 13 for controlling the admission of compressed air to the cylinder 12 in the usual manner. The air cylinder 12 and magnet valve 13 may be of the conventional type and,

2

therefore, will not be described in detail in the present application. An auxiliary or interlocking switch assembly 14 of the usual type may be mounted on the cylinder 12, as shown.

5 An insulator 15 is connected to the external end of the piston rod for the piston disposed in the cylinder 12. A metal yoke 16 is connected to the insulator 15 by means of a bolt 17 and is therefore actuated by the piston in the cylinder 12. A flat metal plate 18 may be secured to the ends of the yoke 16. The plate 18 is utilized to apply pressure to the carbon pile assembly 11 and also to complete an electrical circuit to the carbon pile. The yoke 16 is connected to a fixed terminal 19 by means of a flexible shunt 20.

20 The carbon pile assembly 11 comprises a plurality of carbon plates or discs 21 and 22 and insulating spacing washers 23. A flat metal end plate 24 is provided at one end of the carbon discs, and a flat metal plate 25 is provided at the other end. The carbon discs 21 and 22, the insulating washers 23, and the metal plates 24 and 25 are all slidably mounted on a glass rod 26 which in turn is slidably mounted on a fixed copper rod 27.

25 The copper rod 27 is supported at one end by an angle bracket 28 and at the other end by an angle bracket 29. The brackets 28 and 29 are secured to the base 10. A terminal connection 31 is secured to the end of the copper rod 27 which is mounted in the bracket 28, and the bracket 28 is electrically connected to the end plate 25 by means of a flexible shunt 32. The other end of the copper rod 27 may be silver tipped and is disposed to be engaged by the end of the bolt 17 30 when the carbon pile is substantially fully compressed. The end of the bolt 17 may also be silver tipped.

35 The carbon discs are compressed against a spring 33 which is disposed between the end plate 25 and the bracket 28. The glass rod 26 is compressed against a spring 34 which is disposed inside of the spring 33 between a metal sleeve 35 at the end of the rod 26 and the bracket 28.

40 As illustrated more clearly in Fig. 3, the carbon discs 21 are flat and each disc 22 is undercut slightly on each side as shown. Furthermore, the discs 21 are disposed in pairs with an insulating washer 23 disposed between the discs of each pair. Each pair of the flat discs 21 is disposed between 45 two of the undercut discs 22. Thus, when pressure is applied on the discs, the wide portions of the undercut discs engage the flat discs 21, thereby causing each pair of discs 21 to be deflected toward each other to make contact at their outer edges since their central portions are kept apart

by the spacing washers 23. As the pressure increases, the action is similar to that in the ordinary carbon pile resistor where the resistance decreases as the pressure increases.

Assuming that it is desired to close the switch, the magnet valve 13 is energized to admit air to the cylinder 12, thereby causing the yoke 16 to press the plate 18 against the end plate 24. When the edges of the carbon discs 21 make contact, as described hereinbefore, the electrical circuit is established through the carbon pile which at this time has a relatively high resistance. As the pressure on the carbon pile is increased, the resistance is gradually decreased until finally the contact member 17 engages the end of the copper rod 27. At this time, the switch is entirely closed, and the electrical circuit extends from the terminal 19 through the shunt 20, the yoke 16, the contact member 17, the copper rod 27, and the terminal 31. Under this condition, the carbon pile is shunted from the electrical circuit. In this manner there are no losses in the carbon pile while the switch is carrying current continuously.

When it is desired to open the switch, the magnet valve 13 is deenergized to exhaust the air from the cylinder 12, thereby releasing the pressure on the carbon pile. The first movement of the yoke 16 to the left opens the circuit through the contact member 17 and the rod 27, thereby inserting the carbon pile into the circuit while substantially fully compressed.

As the pressure is removed, and the carbon pile expands, the resistance increases gradually until finally all of the carbon discs 21 separate simultaneously, thereby interrupting the electrical circuit at a multiple number of places. Since, as explained hereinbefore, the flat discs 21 make contact at their outside edges and also break contact at the same place, any arcs caused by interrupting the circuit are at the outside periphery of the carbon pile. When the switch is fully opened, a wide gap exists in the electrical circuit between the contact member 17 and the end of the copper rod 27.

From the foregoing description, it is apparent that I have provided a carbon-break switch which inserts a very high resistance into an electrical circuit when the circuit is opened, thereby reducing the current to almost zero and then opening the circuit in a multiple number of places simultaneously. It is evident that the switch herein described has numerous applications in the electrical field, such as, for example, in the control of electrically propelled vehicles, particularly those operating in mines where it is desirable to avoid the drawing of arcs during the opening of an electric circuit.

Since numerous changes may be made in the above-described construction, and different em-

bodiments of the invention may be made without departing from the spirit and scope thereof, it is intended that all matter contained in the foregoing description or shown in the accompanying drawing shall be interpreted as illustrative and not in a limiting sense.

I claim as my invention:

1. In an electric switch, in combination, a carbon pile having a plurality of undercut carbon discs and a plurality of pairs of flat carbon discs disposed to make contact at their edges when compressed together to establish an electric circuit through the switch, each pair of flat discs being disposed between two of the undercut discs, and spacing means disposed between certain of said discs to cause them to be deflected toward each other when compressed axially, said spacing means having a smaller diameter than said discs.

2. In an electric switch, in combination, a carbon pile comprising a plurality of undercut carbon discs and a plurality of pairs of flat carbon discs, the discs of each pair of flat discs being disposed between two of the undercut discs to make contact at their edges when compressed together to establish an electric circuit through the switch, and a spacing washer disposed between the discs of each pair to cause them to be deflected toward each other when compressed axially, said spacing washer having a smaller diameter than said discs.

3. In an electric switch, in combination, a carbon pile comprising a plurality of pairs of flat carbon discs and a plurality of undercut discs, the discs of each pair of flat discs being disposed to make contact at their edges when compressed together between two of the undercut discs to establish an electric circuit through the switch, and means for compressing the carbon pile axially.

4. In an electric switch, in combination, a carbon pile comprising a plurality of pairs of flat carbon discs and a plurality of undercut discs, the discs of each pair of flat discs being disposed to make contact at their edges when compressed together between two of the undercut discs to establish an electric circuit through the switch, a spacing washer disposed between the discs of each pair of flat discs, and means for compressing the carbon pile axially.

5. In an electric switch, in combination, a carbon pile comprising a plurality of pairs of flat carbon discs and a plurality of undercut discs, a spacing washer between the discs of each pair of flat discs, and means for compressing the discs of each pair of flat discs between two of the undercut discs against said washer to make contact at their edges to establish an electric circuit through the switch, said spacing washer having a smaller diameter than said discs.

CHARLES C. WHITTAKER.
